MOTOR HOUSING AND CENTRIFUGAL PUMP COMBINATION

Rand H. Martin, Monterey Park, Calif., assignor to HPE Inc., El Monte, Calif., a corporation of California

Filed May 5, 1965, Ser. No. 85,117

Term of patent 14 years

(Cl. D65—1)

FIGURE 1 is a side elevation view of a motor housing and centrifugal pump combination showing the new design;

FIGURE 2 is a perspective illustration of the combination from a rear position;

FIGURE 3 is a perspective illustration of the new design from a front position;

FIGURE 4 is an end elevation looking from the left toward the right in FIGURE 1; and

FIGURE 5 is a fragmentary cross-section taken on line 5-5 in FIGURE 4.

The dominant features of the design reside in the portions shown in full lines.

The inlet and outlet tubes, shown fragmentarily and in broken lines, are included for illustrative purposes only.

I claim:

The ornamental design for a motor housing and centrifugal pump combination, as shown and described.
